UNITED STATES PATENT OFFICE.

PATRICK JOSEPH KEENAN, OF CHICAGO, ILLINOIS.

FURNACE-DOOR FRAME.

Application filed June 7, 1923. Serial No. 643,900.

To all whom it may concern:

Be it known that I, PATRICK J. KEENAN, a citizen of the United States, and a resident of the city of Chicago, county of Cook, and 5 State of Illinois, have invented certain new and useful Improvements in Furnace-Door Frames, of which the following is a specification.

My invention relates to improvements in 10 furnace door frames, and especially to the arch castings thereof, and has for its main object to double the life of such casting by making it reversible; and furthermore to construct the parts of the door frame in such 15 a manner that the side portions of the worn out arch castings may be utilized as cheek plates.

Other objects will appear hereinafter.

The invention consists in the combinations 20 and arrangements of parts hereinafter described and claimed.

The invention will be best understood by reference to the accompanying drawings forming a part of this specification, and in 25 which—

Fig. 1 is a front elevation of my invention shown in position on a furnace;

Fig. 2 is a vertical cross section taken on line 2—2 of Fig. 1;

30 Figs. 3 and 4 are horizontal cross sections taken on lines 3—3 and 4—4 of Fig. 1, respectively, and

Fig. 5 is a detailed section showing a steel pipe cast in the arch member or casting.

35 In the drawings I have shown my invention applied to a furnace 8 of usual construction which is lined with bricks 9 and is provided with a vertically slidable door 10 and with buckstays 11 at the sides. Said 40 buckstays may consist of channel bars or any suitable metal beams and extend to the front of the furnace forming part of the door frame and supporting my improved members in position.

45 My improved construction comprises an arch member 12 having an arched lower end or face 13 and a similar upper end or face 13', and side flanges 14 which are provided with openings 15 for receiving 50 bolts 16 which extend through the buckstays 11 to mount the arch members in position. These openings 15 are equally spaced from the ends of the arch member to permit the reversible mounting of said member, and 55 the side portions 17 of said arch members adjacent the side flanges 14 are made of

equal length with said flanges and preferably slightly broader than the flanges.

Means is provided for admitting a cooling fluid to cool the curved arch portions or 60 ends 13 and 13', said means comprising a channel 18 provided in member 12 adjacent its curved end 13 and a channel 18' arranged in the member adjacent the upper curved end 13'. These channels or spaces 65 may be constructed in any desirable size and shape, and may be cored in the arch member 12 as shown in Fig. 2, in which case each end of each of said channels is provided with a threaded stem 19 which may be connected 70 to a main fluid pipe 20 by means of a union or coupling 21 (as best shown in Fig. 3) or in any other approved manner. A door 22 is hinged to the buckstays 11 being held 75 closed by a clasp 23, and with a removable brick 24 provides access to said union and for coupling and uncoupling the threaded stems 19 from the supply pipe 20, as indicated in Fig. 3 of the drawings; or the connection between the channel 18 and pipe 20 80 and the means for admitting access thereto may be constructed in any other suitable manner. Instead of providing a cored channel in the arch member 12 the channel may be provided by using a steel pipe 18^a for 85 said channel, as illustrated in Fig. 5, and by placing this pipe in the mould when the arch member 12 is being cast, its ends extending from the arch member in place of the threaded stems 19 in the preceding form. 90

The door frame further comprises cheek plates 25 having side flanges 26 provided with openings 27 through which bolts 28 pass for mounting the cheek plates in position on the buckstays 11. These cheek plates 25 are preferably constructed of the same length as the flanges 14 and the front strips or portion 17 of the arch member, and the openings 27 in the flanges of said cheek plates are spaced apart and placed in relative positions to correspond to the particular positions of the bolt openings 15 on the side flanges of the arch member in order that when the arch member is worn out the side flanges and adjacent strips or portions 17 may be cut from said arch member as by means of the acetylene torch or in any other manner, and these flanges and strips can then be used as cheek plates and without further alteration.

It is apparent from the above disclosure that with a door frame constructed in ac-

cordance with my invention the life of the entire frame will be considerably lengthened, and that when the lower arched portion of the arch casting 12 has been considerably damaged and eaten away by the flames and heated gases coming out through the open door that said arch member can readily be reversed and the upper end 13' placed in the position of the lower end 13 by loosening the bolts 16, and the coupling 21 from the lower threaded stems 19 and fastening said couplings 21 to the similar threaded stems extending from the channels 18' and by fastening the bolts 16 in position. The cooling fluid will only pass through the lower arched portion which is active and where the cooling effect is required, while the upper channel is left inactive or dead. And when both arch portions of the arch member are sufficiently worn away then the flanges with the attached strips 17 may be cut from the worn out central or arch portion and these flanges and strips can be substituted in place of the cheek plates 25 as soon as the former cheek plates have become worn out and must be removed. It is evident that this particular construction effects considerable economy in the maintenance of furnace door frames.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. Reversible arch means for the door frame of a furnace, said means being provided with similarly shaped upper and lower arch portions and with similar means at its sides arranged for reversibly fastening said arch means in position in said door frame.
2. Reversible arch means for the door frame of a furnace, said means being provided with similar upper and lower arch portions and with similar mounting means for reversibly fastening said arch means in position in said door frame, and having means for admitting cooling fluid through each of said portions.
3. A reversible arch member for a furnace door frame, provided with similar upper and lower faces, and a separate interior channel extending along each face with a

separate inlet and a separate outlet for each of said channels.

4. An arch casting for a furnace door frame, provided with similar curved upper and lower portions, and with side flanges properly arranged for mounting said casting reversibly in position in said door frame.

5. An arch casting for a furnace door frame, provided with similarly arched upper and lower portions, means for admitting cooling fluid through either of said portions, and side flanges with bolt holes correctly positioned for mounting said casting in said door frame with either of said portions downward.

6. A furnace door frame comprising arch means and separate cheek plates, said arch means and plates having mounting means at the sides, all of equal length and being arranged for fastening said mounting means of the arch means in place of said cheek plates.

7. A furnace door frame comprising arch means and separate cheek plates, said arch means and plates having side flanges and attached portions all of equal length, there being mounting means provided in corresponding positions on said flanges for mounting the flanges of said arch means and the attached portions in place of said cheek plates.

8. A furnace door frame comprising buckstays with upper and lower sets of bolts, an arch casting having attaching flanges and adjacent laterally extending strips all of equal length, and cheek plates made from the flanges and adjacent strips of similar arch castings, there being bolt holes provided in corresponding positions in all of said flanges for mounting said arch casting and cheek plates interchangeably in position on said bolts in the buckstays.

9. A furnace door frame comprising a reversible arch member having similarly curved upper and lower portions, separate cheek plates beneath said arch member, said members and plates comprising side flanges and attached lateral strips all of equal length, and means for interchangeably fastening the flanges of said arch member in the upper position of said frame or in the lower position in place of said cheek plates.

In testimony whereof I have signed my name to this specification in the presence of two subscribing witnesses.

PATRICK JOSEPH KEENAN.
